T. N. RUSSELL

CARLINE

Original Filed Jan. 26, 1914

UNITED STATES PATENT OFFICE.

THOMAS NATHAN RUSSELL, OF CHICAGO, ILLINOIS, ASSIGNOR TO CHICAGO CLEVE-
LAND CAR ROOFING COMPANY, OF CHICAGO, ILLINOIS, A CORPORATION OF ILLI-
NOIS.

CARLINE.

Original application filed January 26, 1914, Serial No. 814,518. Divided and this application filed May 4, 1914. Serial No. 836,218. Renewed May 16, 1917. Serial No. 169,117.

To all whom it may concern:

Be it known that I, THOMAS NATHAN RUSSELL, a citizen of the United States, and a resident of Chicago, in the State of Illinois, ⁵ have invented certain new and useful Improvements in Carlines, of which the following is a specification.

My present invention relates in general to car construction and more particularly ¹⁰ to the bodies thereof and has special reference to improvements in the carlines used in framing car roofs, and most specifically to end carlines or end plates.

The principal objects of my present invention are the provision in a body construction involving the use of metallic members, of a carline wherein a given weight ¹⁵ of metal is most advantageously employed in the production of a body of maximum rigidity and strength, a minimum of weight, simplicity of manufacture, avoidance of waste of material, and low cost; the provision of an improved arrangement of combined end carline and filler block forming ²⁰ an end plate construction; the provision of an improved carline construction which is adaptable for employment as a component part of a composite end plate construction; the provision of improved means for securing ²⁵ the end plate in turn to the other members of the car framing, in order to secure the greatest strength and rigidity of the frame and roof construction and attain the greatest resistance to all bending moments ³⁰ and other stresses, together with such other objects as may hereinafter appear.

In attaining the foregoing objects and certain additional advantages to be below disclosed, I have provided the construction ³⁵ illustrated in the accompanying drawings, wherein:—

Figure 1 is a perspective view of the carline before the filler block is placed in position to form the composite end plate structure;

Figure 2 is a plan view of the composite end plate structure;

Figure 3 is a view of the blank from which the carline is manufactured;

Figures 4 and 5 are transverse sectional views of the composite end plate structure

taken on the lines 4—4 and 5—5 of Figure 2, each showing, however, a fragment of a roof purlin in position and supported by a flange of the end carline;

Figure 6 is a fragmentary longitudinal view, partly in vertical section, of a corner of a car body structure, illustrative of the method of attaching the composite end plate structure to such body;

Figure 7 is a sectional view taken on the line 7—7 of Figure 6.

Referring first more particularly to Figures 1, 2 and 3 of the drawing, it will be observed that in manufacturing the carlines 20, embodying my present improvements, I preferably employ a flat rectangular piece, 30, (Figure 3) of sheet or plate metal, or similar suitable material, and press outwardly oppositely inclined flanged portions 31, 32, by bending the sheet along the line indicated at 33 until the portions 31, 32, assume a position at substantially a right angle to the horizontal plane of the strip, the oppositely inclined flanges 31, 32, forming what for the purpose of convenience I will term the compression portion of the carline or end plate, simultaneously pressing outwardly in the opposite direction from such plane as oppositely inclined tension portions, flanges 34 and 35 (which may be seen on inspection of Figure 1), which last named tension portions are formed by bending the sheet along the line indicated at 36, and simultaneously giving the web 37 ⁷⁰ thus formed the markedly curved S section clearly to be seen on viewing Figures 4 and 5, there being no sharp bends at the points *a* and *b*. The carline 20 of said Figure 1 and the composite end plate 19 are of substantially the same construction, save that in the composite end plate the end carline support a filler-block indicated at 19°.

By the employment of suitable dies, cutouts may be made as indicated at 38, 39, for the formation of brackets 40, 40 (see Figures 1 and 3), adapted to bear against the side plates of the body framing, (one indicated at 17, Figure 6), when secured in position, as by bolts 41, bracing the composite end plate or end carline against horizontal or rocking movement relatively to the side

plates 17, the formation of said brackets 40—40 leaving outwardly projecting hangers 42—42 by means of which the carline 20 may also be suspended from the plates 17, bolts 43 (Figure 7) being conveniently employed for securing the carline in predetermined position.

As will be apparent on inspection of Figure 1, the formation of my improved composite end plate or carline by the method just described will provide oppositely inclined compression surfaces 31, 32, gradually increasing in width from the center of the carline 20, toward the ends thereof and thereby giving a maximum width to the projecting hanger portions 42, 42, whereby an additional bracing effect against horizontal strains may be attained, the method referred to further providing tension surfaces 34 and 35, thereby affording a maximum amount of material for the formation of the brackets 40, 40.

On viewing Figures 1, 6 and 7, it will be observed that for the purpose of bringing the ends of the roof sheathing directly down upon the ends of the carlines, that is, upon the hangers 42 thereof, and thereby when intermediate purlins 18 are employed, avoiding the necessity of using filler blocks at such ends, I provide the carlines with bends as indicated at 44^a, 44^a, whereby the principal advantages of my present construction are all retained, but the roof construction is somewhat simplified.

On viewing Figures 4 and 5 it will be observed that the compression surfaces 32 and tension surfaces 35 are preferably extended in opposite directions relatively to the curved web 37, this affording a rest or support for the filler block 19^a of the end plate 19 as is clearly to be seen from inspection of such figures.

Referring now more particularly to Figures 6 and 7, it will be observed that the end posts 21 as here shown are of I-beam construction, the outer ends of the web 44 being cut away from the flanges and bent at a right angle to the body of such web as indicated at 45, whereby they may be attached to the composite end plate structure 19.

The improved structure of carline described in the foregoing specification has certain marked features of advantage among which may be noted the rearwardly extending flanged surface 31—32 which supports the purlins 18 and is in turn supported and braced by and against the side plate 17 by the hangers 42 and brackets 40; the forwardly extending flanged surface 34—35 which supports the filler block 19^a to which may be nailed the sheathing 53; the curved web 37 which is arranged at an angle to the perpendicular and is therefore more rigid and offers greater resistance to twisting strains than would be the case were the web

vertically arranged; and the curved bends between said web and the flanges 31—32 and 33—34, as indicated at *a b* respectively, which offer greater resistance to such bending strains than would sharp bends at such points.

This structure is also advantageous in that the rearwardly extending surface 31—32 affords means for anchoring the end carline in position and tying to other portions of the body or roof structure, such features of construction, however, being claimed in my pending application, Serial No. 814,519, filed January 26, 1914, of which this application is a division.

Having thus described my invention and illustrated its use, what I claim as new and desire to secure by Letters Patent, is the following:

1. A carline having a compression surface and a tension surface of differing contours, the latter having an outer edge lying in a single vertical plane and an obliquely arranged curved web therebetween the upper edge of which lies in a vertical plane parallel to said first-mentioned plane, said compression surface and said tension surface being disposed laterally in opposite directions from said web, and the sum of the width of the parts being substantially the same in cross section throughout the carline.

2. A carline having a compression surface, a tension surface, a web therebetween, said web being obliquely arranged, whereby the compression surface and tension surface lie in part one above the other, and a filler block supported by a projecting edge of one of said surfaces.

3. A carline having a compression surface, a tension surface, a curved web therebetween, said web being obliquely arranged, whereby the compression surface and tension surface lie in part one above the other, and a filler block supported by a projecting edge of one of said surfaces.

4. An S-shaped carline having a compression surface and a tension surface and a curved web therebetween, said surfaces being extended laterally in different directions from said web, and a filler block supported by one of said surfaces adjacent one edge of the latter and supported by said curved portion adjacent the other surface.

5. A carline having compression surfaces oppositely and upwardly inclined and a tension surface and an inclined web therebetween formed with connecting portions of large radius of curvature, said compression and tension surfaces being disposed laterally in opposite directions from said web and arranged to lie in part one above the other.

6. A carline having a compression surface, a tension surface, an obliquely arranged web therebetween, said compression surface and said tension surface being dis-

posed laterally in opposite directions from said web and arranged to lie in part one above the other.

7. A carline having a compression surface, a tension surface, a web therebetween, the two longitudinal halves of the web lying in planes intersecting in plan view at an angle adjacent the center of the carline.

8. A carline having a compression surface, having one edge lying in a single vertical plane, a tension surface having one edge extending beyond said first mentioned edge and lying in a single vertical plane parallel to said first mentioned plane, said tension surface being arranged to lie in part below said compression surface, said tension surface increasing in width progressively towards the center of the carline, and an inclined web connecting said compression and tension surfaces.

9. An S-shaped carline having a curved web portion and a lower flange projecting

beyond the curved part of the web connecting the upper and lower edges of the carline.

25

10. A pressed-steel carline having a substantially Z-shaped cross-section and comprising a web extending longitudinally thereof, and an upper flange and a lower flange projecting horizontally from said web in opposite directions, said upper flange increasing in width from the middle of the carline toward the ends thereof, said lower flange decreasing in width from the middle of the carline towards the ends thereof.
